UNITED STATES PATENT OFFICE.

RACHEL MORRIS, OF CHICAGO, ILLINOIS.

CURTAIN-SECURER.

1,354,678.

Specification of Letters Patent.

Patented Oct. 5, 1920.

Application filed December 10, 1919. Serial No. 343,714.

To all whom it may concern:

Be it known that I, RACHEL MORRIS, a citizen of the United States, residing at Chicago, in the county of Cook and State 5 of Illinois, have invented a new and useful Curtain-Securer, of which the following is a specification.

This invention relates to new and useful improvements in window curtain securers, 10 and it is the primary object of the invention to provide a device of this character to be attached to a window frame, so that the same may secure the curtain associated therewith against movement when the window 15 is open.

A further object of the invention is to provide a device of this character which may be folded to a position in parallel relation with the window frame, when the same 20 is not in use.

With the foregoing and other objects in view which will appear as the description proceeds, the invention resides in the combination and arrangement of parts and in 25 the details of construction hereinafter described and claimed, it being understood that changes in the precise embodiment of the invention herein disclosed, may be made within the scope of what is claimed, without departing from the spirit of the invention.

Referring to the drawing:—

Figure 1 is an elevational view of the device as applied to a window frame, the 35 clamping arm being shown in its operative position, in dotted lines.

Fig. 2 is an elevational view of the same when in its inoperative position.

Fig. 3 is a side elevational view of the 40 curing device in an extended position.

Fig. 4 is a sectional view taken on line 4—4 of Fig. 3.

Fig. 5 is a detail view of one of the caps.

Fig. 6 is a detail view of the opposed cap.

Fig. 7 is a sectional view taken on line 45 7—7 of Fig. 3.

Referring to the drawing in detail, the reference character 5 designates a bracket, which includes a relatively short strip of 50 metal apertured as at 6 to receive securing screws or nails, to enable the same to be positioned on the window frame to which the same is to be applied.

A rib 7 is formed substantially intermediate the length of the bracket member

5, and extends longitudinally thereof for co-operating with the recessed portion 8 formed in the metallic cap 9 supported on one end of the arm 10, to be hereinafter more fully described.

60

An aperture 11 is formed in one end of the arm 10, which aperture registers with the aperture 12 formed in the bracket 5, the registering apertures accommodating the pivot pin 13 for securing the arm to the 65 bracket, but permitting of free movement of the arm with relation to the bracket 5.

It will be seen that due to this construction when the arm 10 is moved to its operative position, the rib 7 is disengaged from 70 the recessed portion 8 of the cap 9, to permit the arm 10 to move to an angle to properly grasp or support the curtain associated therewith.

Pivots secured to the outer end of the 75 arm 10, is a relatively short clamping arm 14 which is provided with a cap 15 having the lugs 16 stamped therefrom and co-operating with the walls of the openings 17 formed in the cap 18, carried by the outer 80 end of the arm 10.

The pivot pin 19 which provides the connection between the arm 10 and arm 14, passes through suitable openings formed in the respective arms 10 and 14, the same being constructed to permit a free pivotal movement of the arm 14 with relation to the arm 10, a predetermined distance.

In operation, the arm 10 is moved from 90 its folded position, to a position at right angles with relation to the frame of the window to which the same is applied, the curtain is then positioned over the upper edge of the arm 10. The relatively short clamping arm 14 is now moved downwardly 95 toward the frame of the window, as indicated in dotted lines in Fig. 1 of the drawing until the same contacts with the upper surface of the curtain.

From the foregoing it is obvious that the 100 relatively short arm 14 co-operates with the upper edge of the arm 10 for clamping the curtain to secure the same against movement caused by the wind passing through an open window.

Having thus described the invention, what I claim as new is:—

A window curtain securing device including a bracket, an arm having pivotal connection with the bracket, a clamping arm 110

pivottally connected to the first mentioned arm at one side thereof, and adapted to lie in parallel relation with the first mentioned arm, said clamping arm adapted to coöperate with the first mentioned arm for clamping a curtain thereto.

In testimony that I claim the foregoing

as my own, I have hereto affixed my signature in the presence of two witnesses.

RACHEL MORRIS.
